UNITED STATES PATENT OFFICE.

JASON C. STEARNS, OF WORCESTER, MASSACHUSETTS.

DESIGN FOR A CIGAR AND CIGARETTE LIGHTER.

Application filed August 31, 1927. Serial No. 23,257. Term of patent 14 years.

To all whom it may concern:

Be it known that I, JASON C. STEARNS, a citizen of the United States, residing at Worcester, in the county of Worcester and State of Massachusetts, have invented a new, original, and ornamental Design for Cigar and Cigarette Lighters, of which the following is a specification, reference being had to the accompanying drawing, forming part thereof.

Fig. 1 is a front view of a cigar and cigarette lighter showing my new design, and

Fig. 2 is an edge view thereof.

I claim:

The ornamental design for a cigar and cigarette lighter as shown.

JASON C. STEARNS.
